UNITED STATES PATENT OFFICE.

JOHN H. B. REA, OF LA FAYETTE, GEORGIA.

RAIL TIE AND FASTENING MEANS.

Application filed October 27, 1927. Serial No. 229,068.

The invention relates both to metal railway ties and to means for fastening rails upon such ties.

One object of the invention is to provide a new and improved tie structure which while being rather simple and inexpensive, will be efficient, rigid, durable and in every way desirable.

A further object is to provide new and improved means for securing the track rails upon the tie, said means being of such construction that rapid and easy manufacture is permitted at small cost, producing however an effective and durable fastening means.

With the foregoing in view, the invention resides in the novel subject matter herein-after described and claimed, the description being supplemented by the accompanying drawing.

Fig. 1 is a top plan view.

Fig. 2 is a side elevation partly in section as indicated by line 2—2 of Fig. 1.

Fig. 3 is a vertical transverse section on line 3—3 of Fig. 2.

Figs. 4 and 5 are disassembled perspective views showing the major portions of the rail fastening means.

In constructing the tie, I make use of two channel bars 6, the upper and lower flanges 7—8 of each bar being in contact with the corresponding flanges of the other bar. Tie-bolts 9 pass through the vertical body portions of the bars 6 to tie these bars together, and spacing sleeves 10 are provided around said bolts to hold said vertical body portions of said bars against inward springing when the bolts are tightened to the maximum.

Central and end plates 11—12 respectively are secured by rivets 13 upon the upper flanges 7 of the bars 6, while additional central and end plates 14—15 are secured upon the lower sides of the lower flanges 8, by rivets 16. All of these plates 11—12—14—15 are provided with vertically bent flanges 17 which lie against the outer sides of the aforesaid vertical body portions of the bars 6, thus providing additional means holding said bars against possible spreading. The lowermost end plates 15 are provided with downwardly bent flanges 18 at their inner edges, to be embedded in the ballast and to thus hold the tie against longitudinal shifting. Secured to these plates 15 and to the flanges 8, by a number of the

rivets 16, is a brace bar 19 which extends longitudinally within the tie and may well be of the bowed form shown in Fig. 2, whereby the same acts as a truss brace between the ends and center of the tie. The center of this bar 19 is provided with an upstanding stud 20 which may well be secured to it by nuts 21, said stud passing upwardly through openings in the flanges 7 and the plate 11 and being provided with a nut 22 contacting with the upper side of said plate. By tightening this nut, the bar 19 may be drawn upwardly at its center and thus effectively placed under such longitudinal tension as to cause it to effectively perform the function for which it is designed that is as a truss brace.

The transverse parallel edges of each plate 12, that is the edges which extend transversely of the tie, are bent inwardly upon themselves and shaped to provide two overhanging flanges 23 and 24, the flange 23 being adapted to engage one base flange 25 of a rail, while the flange 24 is intended to occupy a position spaced outwardly from the other base flange 26 of the rail. Bending the edge portions of the plate 12 to provide the flanges 23—24, not only provides a construction which may be simply and easily manufactured, but provides a double thickness of material through which openings 27 are formed for the reception of the rivets 13.

A tightening plate 28 lies upon the plate 12 and underlies both flanges 23—24, so as to extend under the entire width of the rail base. The edge portion of the tightening plate 28, disposed at the flange 24, is bent inwardly upon itself and shaped to provide a third overhanging flange 29 which is adapted to tightly overlie the base flange 26. One end of plate 28 is bent downwardly to provide a driving flange 30 to be struck with a sledge or the like when driving the tightening plate into position between the rail base and the plate 12. The other end of plate 28 is formed with an opening 31 to receive a suitable key or the like 32 which holds said plate against accidental withdrawal. It will be understood that the distance between the flanges 23 and 24 of the end plate 12 must be greater than the width of the base of the rail in order to permit the base to be seated on the plate 12 between these flanges and the plate 28 is provided to fill the space between the edges of

the flanges of the rail base and the flanges of the plate 12. When the plate 28 is driven in between the base of the rail and the top of the tie and between the edge of the flange 26 of the rail base and the adjacent flange 24 of the plate 12, the opposite flange 25 of the rail base is forced or wedged beneath the opposite flange 23 of the plate 12 so that the base of the rail is tightly gripped between the flange 23 of the plate 12 and the flange 29 of the plate 28. The body of the plate 28 when driven into place between the base of the rail and top of the tie as hereinbefore described, forces the rail upwardly and tightly presses the flange 25 of the rail against the flange 23 of the plate 12 on one side, while the folded edge or outer portion of the flange 29 of the plate 28 is tightly pressed against the flange 24 of the plate 12 on the opposite side. The plate 28 and its flange 29 thus act to tightly hold the rail against both lateral and vertical movement.

Excellent results are obtainable from the details disclosed and they are therefore preferably followed. However, within the scope of the invention as claimed, minor variations may be made.

I claim:

1. A rail fastening means comprising a plate for anchorage upon a tie, said plate having one overhanging flange to overlie one base flange of a rail, and a second overhanging flange for disposition in laterally spaced relation with the other base flange of the rail, and a tightening plate lying upon the first named plate and extending under both of said overhanging flanges to underlie the full width of the rail, the edge of said wedge plate engaged with said second flange being provided with a third overhanging flange to overlie said other base flange of the rail.

2. A rail fastening means comprising a rectangular plate for anchorage upon a tie,

said plate having two of its parallel edge portions bent inwardly and providing overhanging flanges, one of which is adapted to engage one base flange of a rail and the other of which is intended to lie in outwardly spaced relation with the other base flange of the rail, and a flat tightening plate resting on the first named plate under both of said overhanging flanges, the edge of said tightening plate under said other flange being bent inwardly to provide a third overhanging flange to engage said other base flange of the rail, one end of said tightening plate being bent downwardly to form a driving flange, the other end of said tightening plate being formed with an opening to receive a key to hold the tightening plate against withdrawal.

3. A rail fastening means comprising a plate having its opposite ends bent downwardly to form flanges for engagement with opposite sides of a tie, said plate having its opposite side edge portions folded inwardly upon themselves and then upwardly to form overhanging flanges, one of which is adapted to engage one base flange of a rail and the other of which lies outwardly in spaced relation from the other base flange of the rail, said folded edges having apertures adapted to receive bolts whereby the plate is fastened to a tie, and a flat tightening plate resting on the first named plate under both of said overhanging flanges, the edge of said tightening plate under said other flange being bent inwardly to provide a third overhanging flange to engage said other base flange of the rail, one end of said tightening plate being bent downwardly to form a driving flange, the other end of said tightening plate being formed with an opening to receive a key to hold the tightening plate against withdrawal.

In testimony whereof I have hereunto affixed my signature.

JOHN H. B. REA.
